US00D616434S

(12) **United States Design Patent**
Fujita et al.

(10) **Patent No.:** US D616,434 S
(45) **Date of Patent:** ** May 25, 2010

(54) **PERSONAL COMPUTER**

(75) Inventors: **Hiroyuki Fujita**, Tokyo (JP); **Sho Sakai**, Kawasaki (JP)

(73) Assignee: **Fujitsu Limited**, Kawasaki (JP)

(**) Term: **14 Years**

(21) Appl. No.: **29/311,884**

(22) Filed: **Jul. 22, 2009**

(30) **Foreign Application Priority Data**

Apr. 2, 2009 (JP) 2009-007683

(51) **LOC (9) Cl.** 14-02

(52) **U.S. Cl.** D14/315

(58) **Field of Classification Search** ..... D14/315-327, D14/341-345, 331, 130; D18/1, 2, 7, 11; 178/17 A, 17 C; 345/102, 104, 156, 163, 345/168; 341/22, 23; 361/679.08, 679.09, 361/679.26, 679.27; 400/486, 489

See application file for complete search history.

(57) **CLAIM**

The ornamental design for a personal computer, as shown and described.

DESCRIPTION

FIG. 1 is a front perspective view of the front, right and top of a personal computer showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

Broken lines shown in the drawings illustrate portions of the personal computer and form no part of the claimed design.
